UNITED STATES PATENT OFFICE.

MAX LEFKOVITZ AND JULIUS COHEN, OF NEW YORK, N. Y.

SPRING LATCH.

Application filed April 11, 1927. Serial No. 182,560.

This invention relates to spring bolts for latching doors and the like closure.

Among the objects of the invention is to generally improve the construction of spring bolts of the character described so as to provide a device comprising few and simple parts, which are readily assembled to form a rugged structure, which shall be cheap to manufacture, and practical and efficient to a high degree in use.

Other objects of this invention will in part be obvious and in parts hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front elevational view showing a spring bolt embodying the invention applied to a door.

Figs. 2 and 3 are cross-sectional views taken on lines 2-2 and 3-3 in Fig. 1, respectively.

Fig. 4 is a front elevational view showing the bolt in retracted position.

Referring in detail to the drawing, 10 denotes a spring bolt embodying the invention, and is here shown mounted on a side of a door 11 and door frame 12 for latching the door in closed position, only a fragmentary portion of the door 11 and door frame 12 being shown.

The spring bolt 10 is seen to comprise a casing 13 having extension flanges 13^a which form the mounting base for the casing, suitable fastening means such as spaced screws 14 being extended through said flanges for rigidly securing said casing in position. End walls 13^b of the casing 13 form bearings through which a latch bar 15 for latching the door is slidably and rotatably mounted, the front or leading end 15^a of said bar 15 being adapted to be projected into a suitable socket member or keeper 16, the latter being firmly secured to the door frame 12 by suitable means such as screws 17 passing through the flange base 16^a of said keeper, as is clearly shown in Figs. 1 and 2.

To conveniently actuate the latch bar 15, a pin 18 is securely mounted on a mid-portion

of the bar 15 so as to extend transversely thereof through a suitable slot 13^c provided in the casing 13. The slot 13^c may be T-shaped and so formed that when the bar 15 is retracted, the pin 18 may be swung either up or down, as is clear from Figs. 1 and 4. The pin 18 may be riveted or otherwise firmly secured to the bar 15 and has its extended portion 18^a threaded and terminated with a head 18^b. A cylindrical clamping finger-nut 19 is rotatably mounted on said threaded portion 18^a and the casing 13 may have a flattened portion 13^d adjacent the front end of the slot 13^c against which the nut 19 is adapted to seat for positively retaining the latch bar 15 in its extended position. A suitable compression spring 20 may be fitted over the rear end 15^b of the bar 15 within the casing 13, said spring having one end thereof abutting the rear wall of casing 13. A washer is interposed between the other end of said spring and the pin 18 to form an even bearing support for said spring end. (See Figs. 2 and 3.)

The rear bar end 15^b extending through the casing may be provided with a head 15^c to limit the forward movement of the bar and to eliminate any possible strain on the pin 18 when the bar 15 is projected forwardly, the slot 13^c being extended to provide a clearance for the pin 18 at its forward end 13^a when the head 15^c abuts the end wall of the casing 13, as is clearly shown in Fig. 2.

The operation of the improved device will now be clear. With the latch bar retracted as shown in Fig. 4 to project said bar 15, the finger-nut 19 is turned to move outwardly on the threaded pin portion 18^a, the head 18^b preventing the accidental removal of said nut from the pin. The pin is then swung from its substantially vertical to a horizontal position. The spring then being in compression projects the bar into the socket member or keeper 16. The finger-nut is next rotated to seat on the flattened casing portion 13^d for securing the bar 15 in its projected position. It should be noted that the bar cannot be retracted by any sliding or rotary movement thereof until the finger-nut 19 is released from its seat, thus providing against unauthorized retraction of the bar for releasing the bolt from the side of the door opposite that on which said bolt is mounted.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

Having thus described our invention, we claim as new and desire to secure by Letters Patent:—

1. In a device of the kind described, a casing, a keeper, a bolt slidably and rotatably mounted in said casing and movable into said keeper, a spring for urging said bolt into latching position, said casing having a slot provided with a lateral extension, a pin connected to said bolt and extending through said slot, said pin movable in said slot for sliding said bolt to retracted position and movable in the extension of said slot for rotating said bolt and for holding it in retracted position, and means for releasably securing said bolt against both translation and rotation in both positions of the bolt.

2. In a device of the kind described, a casing, a keeper, a bolt slidably and rotatably mounted in said casing and movable into said keeper, a spring for urging said bolt into latching position, said casing having a slot provided with a lateral extension, a pin connected to said bolt extending through said slot and movable therein for sliding said bolt to retracted position and movable in the extension of said slot for rotating said bolt and for holding it in retracted position, and a finger piece adjustably mounted on said pin and releasably engageable with the casing to secure said bolt against translation when moved into said keeper and against rotation when in retracted position with said pin in the lateral extension of said slot.

3. In a device of the kind described, a casing, a keeper, a bolt slidably and rotatably mounted in said casing and movable into said keeper, a spring for urging said bolt into latching position said casing hav-

ing a slot provided with a lateral extension, a pin connected to said bolt and extending through said slot, said pin movable in said slot for sliding said bolt to retracted position and movable in the extension of said slot for rotating said bolt and for holding it in retracted position, and means for releasably securing said bolt against both translation and rotation in both positions of the bolt, said bolt having a head at one end to limit the movement of the bolt in the casing, and said slot being extended to provide clearance for the pin to prevent possible strain thereon.

4. In a device of the kind described, a casing, a keeper, a bolt slidably and rotatably mounted in said casing and movable into said keeper, a spring for urging said bolt into latching position said casing having a slot provided with a lateral extension, a pin connected to said bolt and extending through said slot, said pin movable in said slot for sliding said bolt to retracted position and movable in the extension of said slot for rotating said bolt and for holding it in retracted position, and means for releasably securing said bolt against both translation and rotation in both positions of the bolt, said casing having a flattened portion adapted to be engaged by said securing means.

5. In a device of the character described comprising a casing having end walls, a bar slidably mounted in said casing and projecting through said end walls, said casing having a slot, a pin connected to said bar and extending through said slot, and a compression spring coiled about said bar in said casing and positioned between one end wall thereof and said pin, said bar having at one end thereof a head positioned externally of the casing so as to limit the movement of the bar through the casing, said slot being long enough to provide a clearance for the pin when the head of the bar abuts the end of the casing, whereby to prevent the pin from being impelled by the spring against an end of the slot.

In testimony whereof we affix our signatures.

MAX LEFKOVITZ.
JULIUS COHEN.
